UNITED STATES PATENT OFFICE.

HARRY M. NAUGLE AND ARTHUR J. TOWNSEND, OF CANTON, OHIO, ASSIGNEES, BY
MISCELLANEOUS ASSIGNMENTS, TO JONES & LAUGHLIN STEEL CORPORATION, OF PITTSBURGH, PENNSYLVANIA, A CORPORATION OF PENNSYLVANIA.

STEEL-JOIST MANUFACTURE.

Application filed February 17, 1922. Serial No. 537,259.

To all whom it may concern:

Be it known that we, HARRY M. NAUGLE and ARTHUR J. TOWNSEND, citizens of the United States, residing at Canton, in the county of Stark and State of Ohio, have invented a new and useful Improvement in Steel-Joist Manufacture, of which the following is a specification.

The invention relates to apparatus for making steel joists and the like for use in building construction in places where standard rolled structural shapes may not be used because of the excessive weight or improper distribution of the metal therein; and the object of the invention is to expand the web portion of a rolled I-beam or other structural shape into an integral lattice portion in such a manner that the strength of the lattice will be co-ordinated with that of the flanges without any excess metal being present in any portion of the beam.

The expansion of the web of a flanged beam, which has been slit to form bars and bonds, necessarily requires a stretching or elongation of the bars because the length of the flanges cannot be shortened. An elongation of bars effected solely by a lateral separation of flanges, can only be accomplished to a limited extent, even though the same is done at a working heat. When more than a single row of bars is involved, difficulty is experienced in uniformly elongating the same and in preventing a rupture or buckling of the bars at the angle of their connection with the bonds.

The desired expansion may be accomplished by initially expanding the slit web of a beam by a separation of the flanges and an elongation of the bars, followed by a further elongation of the bars by a deflecting of the intermediate rows of bonds from the plane of the web by means of a roll operating between the flange bonds to deflect bodily the bars and intermediate bonds, as set forth in our pending application, Serial No. 524,996, filed December 27, 1921.

The present improvement involves the use of a stationary guide die to act upon the intermediate bonds and bars, to partially deflect the bonds and deploy and elongate the bars and incline them downward in front of a deflecting and elongating roll, so as to reduce the angle of incidence therewith, and facilitate the proper operation of the same,

and to permit the use of a roll of a minimum 65 diameter.

The accompanying drawings, forming part hereof, show an illustrative apparatus for expanding a rolled I-beam in accordance with the present improvement. In the drawings:

Figure 1 (in two parts) is a vertical section, on the longitudinal axis of the apparatus;

Fig. 2 is a plan view, partly in section, of 65 an I-beam in process of expansion, showing a plan of the first driving and flattening rolls, and a horizontal section of the deflecting die and deflecting roll in the plane of the web of the beam;

Fig. 3 is a cross section on line III—III, Figs. 1 and 2, through the forward end of the stationary deflecting die;

Fig. 4 is a cross section on line IV—IV, Figs. 1 and 2 near the rear end of the sta- 75 tionary deflecting die;

Fig. 5 is a cross section on line V—V, Figs. 1 and 2, through the axis of the deflecting rolls;

Fig. 5^a is a similar section of a modified 80 deflecting roll;

Fig. 6 is a fragmentary side plan of an I-beam;

Fig. 7 is a cross section of the same;

Fig. 8 is a plan of the same, showing 85 the web slit to form bars;

Fig. 9 is a cross section of the same on line IX—IX, Fig. 8;

Fig. 10 is a fragmentary elevation of the nip of the bar flattening rolls, showing an 90 I-beam in section with a slit web flattened between the rolls;

Fig. 11 is a fragmentary elevation of the nip of the web flattening rolls, showing a 95 fully expanded beam in section with its web flattened between the rolls; and

Fig. 12 is a fragmentary plan of a fully expanded and flattened lattice web.

Similar numerals refer to similar parts throughout the drawings.

The apparatus may include slitting rolls 13 and 13' and flattening rolls 14 and 14' preceded respectively by beam guides 15 and 15' and 16 and 16'; and in rear of the bar flattening rolls are located stationary guides 105 17 and 17' extending rearward to a bond deflecting roll 18, from which stationary guides 19 and 19' extend rearward to web

flattening rolls 20 and 20', which may deliver the expanded beam upon a table 21.

The stationary guides 17 and 17' may include intermediate body bars 22 and 22' carried by transverse supports 23 secured to the roll housings 24 and 25; on the sides of which body bars are formed or secured guide plates 26 and 26', the outer faces of which are shaped to fit the flanges, and are longitudinally diverged so as to separate the flanges as the beam under treatment is propelled rearward by and from the flattening rolls 14 and 14'.

For the purpose of the present improvement, the I-beam should be received at a working heat of about 1500° F. which may come directly from the finishing rolls of a shape rolling mill, or may be obtained from a reheating furnace. The initial portion 20 of the expansion requires but a little elongation of the bars, and the same may be accomplished solely by a separation of the flanges of the beam by the diverging guides, which operation serves directly to diverge 25 and elongate the bars to deploy them in the plane of the web.

The initial expansion may be accompanied or immediately followed by an initial deflection of the intermediate bonds, which, 30 as shown in Fig. 1, is accomplished by a deflecting guide or die 27, which may be formed on or depend from the underside of the body portion 22 of the guides 17.

The stationary deflecting die 27 operates 35 on the intermediate bonds 28 of an I-beam slit as shown in Fig. 8 so as to deflect them from the plane of the web and incline them downward to lessen the angle of incidence with the periphery of the deflecting roll 18, 40 at the same time initially elongating the bars 29 connecting the intermediate bonds with the flange bonds 30 of the I-beam.

The deflecting roll 18 may be integral 45 with flange diverging rolls 31, as shown in Fig. 5, or the deflecting roll 18' may be journaled between flange driving rolls 31', as shown in Fig. 5'. The periphery of the 50 deflecting roll may be slightly rounded transversely and its width is such as to permit it to enter between the flange bonds 30 of the I-beam, as the same have been spread apart where the beam reaches the deflecting roll.

The action of the deflecting roll elongates 55 the bars 29 to the full extent required for the full expansion of the web, by displacing the intermediate bonds further from the plane of the web than they have been displaced by the stationary guide die 27.

The guides 19 and 19' extending rearward from the deflecting roll 18 are provided on each side with plates, like the plates 26 and 26' of the guide 17, which slidably engage the flanges and are longitudinally 60 diverged so as to continue the separation

of the flanges until the expansion of the web is complete at the rear ends of the guides 19 and 19'. The separation of the flanges serves to swing the deflected intermediate bonds toward the original plane of the web, and the rolls 20 and 20' serve to flatten and set the bonds and fully elongated bars into a common plane, to form the completely expanded web of the I-beam, as shown in Figs. 11 and 12.

The use of a stationary die for initially deflecting the intermediate bonds, permits the use of a deflecting roll with a comparatively small diameter for fully deflecting the bonds without wedging between the bars or straining the metal at the junction of the bars with the bonds; and the method of initially deflecting the intermediate bonds during the initial separation of the flanges materially shortens the length of the apparatus required for the expanding process.

We claim:

1. Apparatus for expanding the web of a structural shape or the like slit to form bars and bonds, including means laterally separating the bonds in the plane of the web to expand the latter initially, means deflecting intermediate bonds from the plane of the web to elongate the bars, and means further separating the adjacent bonds to expand the web fully.

2. Apparatus for expanding the web of a structural shape or the like slit to form bars and bonds, including means initially operating upon the intermediate slit portion of the web to elongate the bars, cooperating rollers further operating upon said intermediate portion for bodily deflecting and fully elongating the bars, and means laterally separating the bars and bonds for expanding the web.

3. Apparatus for expanding the web of a structural shape or the like slit to form bars and bonds, including means separating the bonds to expand the web initially, means deflecting intermediate bars initially to elongate the bars initially, means further deflecting said bonds to elongate the bars fully, and means further separating adjacent bonds for fully expanding the web.

4. Apparatus for expanding the web of a structural shape or the like slit to form bars and bonds, including means separating the bonds to expand the web initially and means simultaneously deflecting intermediate bars initially to elongate the bars initially, means for further deflecting intermediate bonds to elongate the bars and means for further separating adjacent bonds fully for fully expanding the web.

5. Apparatus for expanding the web of a structural shape or the like slit to form bars and bonds, including a stationary die initially deflecting intermediate bonds to elongate the bars, a roller die further de-

- flecting intermediate bonds for fully elongating the bars, and means laterally separating the adjacent bonds for expanding the web.
- 5 6. Apparatus for expanding the web of a structural shape or the like slit to form bars and bonds, including means separating the bonds to expand the web initially, a stationary die initially deflecting intermediate 10 bonds to elongate the bars, a roller die further deflecting intermediate bonds to elongate the bars fully, and means further separating adjacent bonds for fully expanding the web.
- 15 7. Apparatus for expanding the web of a structural shape or the like slit to form bars and bonds, including rolls for operating on the slitted web, stationary diverging guides for engaging and separating the edges 20 of the shape to separate the bars, rolls for receiving the partially expanded shape and bodily deflecting the deployed bars and bonds to tension and elongate the bars, and stationary diverging guides engaging and 25 further separating the edges of the shape for further expanding the web.
8. Apparatus for expanding the web of a structural shape or the like slit to form bars and bonds, including rolls initially operating upon the slitted web, guides receiving said shape from said rolls and having portions for deploying the slitted portion of said web to partly expand said shape, and
- roller means for receiving said partly expanded shape and further operating on said 30 deployed slitted portion, said roller means comprising grooves for holding the edges of said shape and a circumferential enlargement for deflecting the intermediate bonds to separate the bars, and flattening guides 40 for receiving said expanded shape from said roller means and widening and flattening it.
9. In apparatus of the character described, roller means comprising grooves for holding the edges of a structural shape or the like 45 having an intermediate portion slit to form bars and bonds, and means having a circumferential enlargement for deflecting said intermediate portion to separate the bars.
10. In apparatus of the character de- 50 scribed, mating roller means comprising grooves for holding the edges of a structural shape or the like having its web slit to form bars and bonds, said roller means having a circumferential enlargement for deflecting 55 the slit web to separate the bars, and means for driving said roller means in unison.
11. In apparatus of the character de- 60 scribed, grooved rolls for holding the edges of a structural shape or the like slit intermediate its edges to form bars and bonds, one of said rolls having a circumferential enlargement for deflecting the slit portion to separate the bars.

HARRY M. NAUGLE.
ARTHUR J. TOWNSEND.
